PERMEABILITY TUNING MECHANISM

William A. Schaper, Cicero, Ill., assignor to Aladdin Industries, Incorporated, a corporation of Illinois

Application February 28, 1947, Serial No. 731,481

9 Claims. (CL 74—10.7)

1

The invention pertains to an improved construction of permeability tuning mechanisms by which the movement of a ferro-magnetic core or cores relatively to a corresponding inductance coil or coils is assured to vary the inductance of the coil or coils as required for permeability tuning purposes, which construction at the same time provides a minimum of bulk for the casing of the tuning mechanism, consistent with the proper operation of the inductance coil or coils.

The invention includes a casing having a U-shaped sheet metal member comprising the bottom and end walls of the casing, and parallel side walls of sheet insulating material having notched ends cooperating with notches in the end walls of the casing to interlock the parts and hold the side walls in parallel position. The mechanism also includes an operating shaft extending between the side walls and having on its end portions adjacent the side walls, drums to which flexible bands are secured, said bands also being connected with a cross-head structure movable longitudinally of the side walls by rotation of the shaft. The cross-head structure includes a cross member of insulating material extending transversely of the side walls, connected at its ends with side members extending parallel with the side walls of the casing, and having shoes for sliding engagement with the side walls to retain the cross-head side members in parallelism with the side walls as the cross-head structure is moved from one position to another relatively to the casing side walls. As a result of positively driving each of the cross-head side members from the rotary shaft by means of the flexible bands referred to, equal movements in the same direction are imparted to the cross-head side members for any given rotary movement of the shaft, and as a result, the transverse member of the cross-head maintains a constant angle with the casing side walls for all of its positions resulting from operation of said shaft. The cross-head side members are preferably rigidly connected with the transverse member of the cross-head at substantially right angles and this assists in maintaining the transverse member of the cross-head at a constant angle to the side walls of the casing for all positions of the cross-head resulting from operation of the shaft. Coil forms are suitably supported in the casing and are preferably parallel with each other and with the side walls of the casing, and ferro-magnetic cores contained in said coil forms are connected with the transverse member of the cross-head so that said cores have

2

equal movements imparted to them in the same direction for any rotary movement of the shaft.

The object of the invention is to construct a permeability tuning mechanism having the structure and advantages described and to provide in such tuning mechanisms, improved supports for coil forms, in the manner below described, as a result of which the entire tuning mechanisms are compact, simple in construction, positive and accurate in operation, and inexpensive to manufacture.

The invention will be best understood by reference to the accompanying drawings illustrating preferred embodiments thereof, in which:

15 Fig. 1 shows in plan view a tuning mechanism provided with two parallel coil forms and associated parts;

Fig. 2 is a side elevation of the structure shown in Fig. 1;

20 Fig. 3 shows in vertical section, and to an enlarged scale, a part of the structure shown in Fig. 2, taken along the line 3—3 in Fig. 2;

Fig. 4 is a longitudinal vertical section through the structure shown in Fig. 1, taken along the line 25 4—4 in Fig. 1;

Fig. 5 shows in plan view a tuning mechanism similar to that shown in Fig. 1 but with the parts thereof in modified arrangement, the structural details of parts of the tuning mechanism shown 30 in Fig. 5 being different from the corresponding details shown in Fig. 1;

Fig. 6 shows in side elevation the structure illustrated in Fig. 5;

Fig. 7 shows in vertical longitudinal sectional view the structure illustrated in Fig. 5, taken along the line 7—7 in Fig. 5;

Fig. 8 is a vertical sectional view of part of the structure shown in Fig. 6, taken along the line 35 8—8 in Fig. 6;

Fig. 9 is a vertical sectional view of a part of the structure shown in Fig. 6, taken along line 9—9 in Fig. 6;

Fig. 10 shows in side elevation the coil form mounting mechanism illustrated in Figs. 5, 6 40 and 7;

Fig. 11 is a plan view of the mounting mechanism shown in Fig. 10;

Fig. 12 shows in a view similar to Fig. 7 a modification of the structure there illustrated, by 50 which coil forms are supported in two horizontal planes one above and spaced from the other and by which the transverse member of the cross-head is vertically extended for connection with the movable ferro-magnetic cores in the upper plane 55 of the coil forms, as well as for connection with

the ferro-magnetic cores in the lower plane of said coil forms, and

Fig. 13 shows in a view similar to Fig. 1, an extended form of the construction illustrated in Fig. 1, by which more than two tuning units may be mounted in the same casing in substantially the same horizontal plane.

Similar numerals refer to similar parts throughout the several views.

As shown in Figs. 1 and 2, the casing of the tuning mechanism includes end walls 1 and 2 and a bottom wall 3 formed by correspondingly bending a sheet of metal of proper size, and between the end walls 1 and 2 side walls 4 and 5 of sheet insulating material are supported in parallel vertical planes, by having the ends of the side walls notched to engage corresponding notches in the end walls 1 and 2 so that the side walls have interlocking engagement with the end walls and are secured thereto without the use of additional fastening devices.

A shaft 6 extends horizontally between and transversely of the side walls 4 and 5 and also through said side walls to support drums 7 and 8 which are rigidly secured to the shaft adjacent the outer surface of the said side walls. The end portions of the side walls also support adjacent their outer surfaces, idler wheels 9 and 10 in line with the drums 7 and 8 respectively, and flexible bands 11 and 12 extend around the idler wheels 9 and 10 respectively, and are also connected with the corresponding drums 7 and 8.

As shown in Figs. 2 and 4, the upper edges of the side walls 4 and 5 are in line with the upper edges of the end walls 1 and 2, and said side walls are substantially narrower vertically than said end walls, leaving a substantial space between the lower edge of each side wall and the inner surface of the bottom wall 3. A transverse member 13 of sheet insulating material is mounted to extend at substantially right angles with the side walls 4 and 5 and in a vertical plane, so that it rests at its lower edge on the bottom wall 3 and extends at its end portions under and slightly beyond the outer surfaces of the side walls 4 and 5. The projecting ends of the transverse member 13 are rigidly secured for the relation of the parts shown in Figs. 1, 2 and 4, with the left-hand ends of the cross-head side members 14 and 15, which are preferably of sheet material and disposed in vertical planes parallel with and adjacent the outer surfaces of the side walls 4 and 5, respectively. The cross-head side members 14 and 15 are preferably made of insulating material and are provided with tongues extending through corresponding notches in the transverse member 13 and the parts are secured in this position by suitable adhesive. As a result of the construction described, the left-hand ends of the side members 14 and 15 are restricted against vertical movement by the bottom wall 3 and the sliding engagement of the member 13 with the lower edges of the side walls 4 and 5. The other ends of the members 14 and 15 are provided with sliding shoes as illustrated for the side member 15 in Fig. 2 at 16, each of these shoes comprising a piece of sheet metal formed as more clearly shown in Fig. 3 to interlock with the side member 15 and extend therefrom under the side wall 5 inside of which, said shoe is provided with an un-turned flange 17, a part of the shoe being provided outside of the side wall 5 with an up-turned flange 18, so that the flanges 17 and 18 restrain the right-hand ends of the side mem-

bers 14 and 15 from movement away from parallelism with the side walls 4 and 5.

Each of the cross-head side members is provided as illustrated for the side member 15 in Fig. 2 with notches 19 and 20 for engagement by portions of the flexible bands 11 and 12, which bands may consist of cord, flexible wire or equivalent material. As shown in Fig. 2, a first portion of the flexible band 12 extends from the drum 8 around the idler wheel 10 and is connected at its end with the side member 15 at the notch 20, and the remaining portion 12a of the flexible band extends from the lower portion of the drum 8 for engagement with the notch 19 in the side member 15, a suitable spring 8a being mounted in the drum 8 to maintain a desired tension on the parts of the flexible band 12, 12a. As a result of the construction described, rotary movement of the shaft 6 imparts movement to the transverse member 13 of the cross-head to the left or to the right, according to the direction of movement of the shaft, and by such shaft movement in one direction, the transverse member 13 may be moved nearly or quite into engagement with the end wall 1, and by reverse movement of the shaft 6, the right-hand ends of the side members 14 and 15 may be brought nearly or quite into engagement with the end wall 2. Bearing in mind that the side members 14 and 15 need be no longer than required for mechanical considerations to insure the holding of the transverse member 13 at a constant angle to the side walls 4 and 5, it will be observed that the described construction of cross-head, and the relation thereto of the flexible bands 11 and 12, produces a casing structure which is most compact in the direction of the length of the side walls of the casing, for any required movement in the direction of the side walls of the transverse member 13, bearing in mind that the ferro-magnetic cores below described as operated by the transverse member 13 must have a certain length to perform their functions, and the result of the structure is as illustrated in Fig. 4, to make the length of the casing substantially twice the length of the coil form or coil forms constituting a part of the tuning mechanism.

As shown in Figs. 1 and 4, a coil form 21 is supported in horizontal position parallel with the side walls of the casing by a mounting structure comprising sheet insulating material bent to channel formation as shown at 22, so that the edge portions of said supporting structure rest on the bottom wall 3, a part of the bottom wall being bent upwardly at 3a to clamp the right-hand lower edge portion of said supporting structure to the end wall 2, and the other lower edge portion of said supporting structure being provided with a tongue 22a extending through a corresponding opening in the bottom wall 3 and held in that position by suitable adhesives. The supporting structure 22 is limited in height to that required for proper operation of the coil or coils supported by the coil form 21, and the shaft 6 is given a vertical location relatively to the side walls 4 and 5 such that it is just above and slightly out of contact with the coil form support 22, thereby reducing the vertical height of the casing of the tuning mechanism to the minimum amount permitted by proper operation of the coils on the coil forms.

The tuning mechanism described is of the kind known as permeability tuning mechanism, by which ferro-magnetic cores are provided in the

coil forms of the apparatus and are movable axially therein to secure different amounts of inductance of the coils on the coil forms for different positions of the cores in the coil forms. As shown in Fig. 1, a second coil form 23 is supported in parallel relation with the side walls 4 and 5 and with the coil form 21, by the coil form support 22, and ferro-magnetic cores 24 and 25 are mounted for axial movement in said coil forms, said cores being connected by slender rods 26 and 27 respectively, with the transverse member 13 of the cross-head, as a result of which, operation of the cross-head as described, simultaneously moves the cores 24 and 25 corresponding amounts in the same direction relatively to the coil forms 21 and 23, for any given operation of the shaft 6.

Inductance windings are not shown on the coil forms illustrated, since their use in connection with the coil forms is well known and understood, and for the further reason that the present invention is not concerned with the electrical operation of the apparatus, but with the structure by which compact and effective tuning mechanisms are produced. As is well known, variable inductance mechanisms of the kind described are frequently employed as the tuning means for resonant circuits involving the use of fixed capacitors, and where the mechanism of the invention is used for that purpose, the coil form support 22 forms a convenient support also for capacitors 28 and 29 for use respectively with inductance coils supported by the coil forms 21 and 23. In many cases it is desired in radio receivers to use two permeability tuning devices in cooperation with each other, for example as an antenna tuner and also as an oscillator tuner, and for this purpose the double unit illustrated in Figs. 1, 2 and 4 is well adapted. The invention, however, is not restricted to the use of any particular number of tuning units in the entire mechanism mounted in a single case, since the compactness of the structure and the efficacy of its operation are available equally where any number of tuning devices are mounted in the same casing.

In the modified construction of the tuning mechanism illustrated in Figs. 5-11 inclusive, the casing includes end walls 30 and 31 and a bottom wall 32 of sheet metal bent into a U-shape and having interlocking engagement with the ends of the side walls 33 and 34 which are of insulating sheet material having notched ends engaging corresponding notches in the end walls to effectively secure the side walls to the end walls. With this construction, an operating shaft 35 extends between and through the side walls 33 and 34 and transversely of said side walls, but in this case said shaft is located in the lower portion of the casing instead of being located in the upper portion thereof as shown in Figs. 1, 2 and 4. With the construction illustrated in Figs. 5-7 inclusive, the shaft 35 has secured to its ends adjacent the outer surfaces of the side walls 33 and 34, drums 36 and 37 in line with idler wheels 38 and 39 respectively, which are supported by side walls 33 and 34. Flexible bands 40 and 41 extend around the drums 36 and 37 and the idler wheels 38 and 39 respectively, to operate the cross-head of the structure by rotary movement of the shaft 35 in substantially the manner described above for the construction illustrated in Figs. 1, 2 and 4. The cross-head shown in Figs. 5, 6 and 7 includes a transverse member 42 of sheet insulating material rigidly connected at its end portions with sheet metal shoes 43 and 44 which

have an angular cross section in sliding engagement with the upper edges of the side walls 33 and 34. As shown in Figs. 8 and 9, the lower portion of the sliding shoe 44 is bent outwardly away from the side wall 34 as indicated at 44a and 44b. To facilitate connecting the flexible band 41 with said sliding shoe, said band consists of two portions 41a and 41b, the portion 41a extending from the drum 37 around the idler wheel 38 and to the left-hand end of the shoe 44 where said band is held in engagement with said shoe by a projecting lug 44c of said shoe, and the band portion 41b extends from the drum 37 to the other end of the shoe 44 where it is connected with said shoe by means of a notch 44d at the end of said shoe. The shoe 43 is similarly formed and similarly connected with the band 40 which comprises similar portions connected with the drum 36 and with the shoe 43 as described for the band 41 and shoe 44. The transverse member 42 has a length making it a sliding fit between the side walls 33 and 34 and as a result of the shoes 43 and 44 extending adjacent the outer surfaces of the side walls 33 and 34, displacement of the cross-head in a horizontal plane relatively to the side walls is prevented.

As shown in Fig. 6, the side wall 34 is provided with a slot 45 parallel with the upper edge of said side wall, to receive bent lugs 44e and 44f extending into the slot 45 from the shoe 44, which lugs together with the engagement of the upper edge of the side wall by the shoe 44, restrain the cross-head from vertical displacement relatively to the side wall. The shoe 43 and side wall 33 are formed in a similar manner to that described for the shoe 44 and side wall 34 and have similar engagement with and relation to each other, as a result of which the cross-head is supported for longitudinal sliding movement on the side walls 33 and 34 and restrained from displacement relatively to the side walls in all directions, the only movement of the cross-head permitted by the construction being a sliding longitudinal movement relatively to the side walls 33 and 34 produced by the action of the flexible bands 40 and 41 by imparting turning movement to the shaft 35. With the construction shown in Figs. 5, 6 and 7, the side walls 33 and 34 are of less width than the height of the end walls 30 and 31, as a result of which, with the lower edges of the side walls 33 and 34 resting on the bottom wall 32 of the casing, a clearance is provided above the upper edges of the side walls and below the upper edges of the end walls within which the cross-head structure may move without interfering with other parts that may be adjacent the tuning mechanism in a complete assembly of apparatus.

As shown in Fig. 7, provision is made in the casing to support one or more coil forms 46 in horizontal position parallel with the side walls 33 and 34, above the shaft 35, instead of locating the coil forms below the operating shaft as shown in Figs. 1, 2 and 4. Each of the coil forms 46 illustrated in Figs. 5 and 7 is provided with a supporting structure more clearly shown in Figs. 10 and 11, which includes a strip of sheet insulating material 47 bent into a U-shape and provided at its right-hand ends with a strip of sheet insulating material 48 extending between the right-hand end portions of the bent strip 47 and having interlocked and notched engagement with said end portions and secured in place preferably by suitable adhesive, the strip 48 having an aperture therein supporting the right-hand end of the coil form 46. In the other end of the bent mem-

ber 47, a flat piece of sheet insulating material 49 is disposed which extends through and above and below the bent member 47, and which has interlocking notched engagement with the member 47 to hold the parts in proper position by means preferably of suitable adhesive. The member 49 is provided with an aperture supporting the left-hand end of the coil form 46, so that by suitably supporting the member 49 the coil form is given definite support in the casing of the tuning mechanism. As shown in Fig. 7, the upper edge of the member 47 of each of the coil form supporting structures is in the horizontal plane of the upper edges of the side walls 33 and 34, and the member 49 extends below the member 47 sufficiently to engage and be supported by the bottom wall 32 of the casing. The member 49 extends above the member 47 nearly to the upper edge of the end wall 30 and bent tongues 30a and 32a formed from the end wall 30 and bottom wall 32, engage the upper and lower edges of the member 49 to positively hold the coil form support in proper position. Each of the coil forms 46 is preferably provided with its own supporting structure independently of the other coil forms.

For the purpose of securing a variation in inductance of the inductance windings mounted on coil forms 46, each of said coil forms is provided with a ferro-magnetic core 50 movable axially in said coil form and connected by a slender metal rod 51 with the transverse member 42 of the cross-head, so that by rotary movement of the shaft 35 all of the ferro-magnetic cores of the tuning mechanism are simultaneously moved in the same direction and to the same extent, depending upon the amount of rotary movement of said shaft. Where the inductance windings mounted on the coil forms 46 are used as parts of tuned resonant circuits, tuning capacitors may conveniently be mounted on the end wall 31 as illustrated at 52 and 53. To prevent lateral displacement of the mid-portions of the side walls 33 and 34, the bottom wall 32 preferably has formed from it, tongues 32b engaging opposite sides of the lower portions of the side walls as indicated.

The construction illustrated in Figs. 5-11 inclusive has all of the advantages described in connection with Figs. 1, 2 and 4 and operates in substantially the same manner to secure substantially the same results.

The construction of tuning mechanism thus far described, is adapted for use where one or more coil forms and tuning cores are used in the tuning mechanism in a single horizontal plane. In some cases it is desired to simultaneously operate tuning units located in two horizontal planes, one above the other, either to avoid the undue width of the casing resulting from the number of units employed or because of desiring to have the height of the mechanism as a whole more nearly equal to its width, as may be desired in some assemblies of apparatus. The construction illustrated in Figs. 5, 6 and 7 is readily adapted with small modification, to simultaneously operate tuning units in a plurality of horizontal planes one above the other and with a plurality of said units in each of said planes as illustrated in Fig. 12. With this construction, the casing of the mechanism is the same as described in connection with Figs. 5, 6 and 7 and the cross-head construction is operated in the same manner as there described, the only difference in connection with the cross-head construction being that the transverse member 54 is made higher

and extends above the casing of the mechanism to be connected with the core rods 55 of the upper tuning units. With this construction, the coil forms 56 and 57 in the upper and lower horizontal planes of units are preferably supported in a manner similar to that illustrated in Figs. 10 and 11, a U-shape supporting member 58 and cross-member 59 being employed for each coil form and having the same construction and relation to the coil form as described for the members 47 and 48 in connection with Figs. 10 and 11.

With the construction of Fig. 12, the member 49 of Figs. 10 and 11 is replaced by a similar member 60 which is extended sufficiently above the end wall 30 to support the coil form or forms 56 in the upper horizontal plane of said coil forms, the manner of supporting the members 58 from the members 60 being the same as described in connection with Figs. 10 and 11 for supporting the member 47 from the member 49. With the construction of Fig. 12, the member 60 of the coil form support rests on the bottom wall 32 of the casing and is held in vertical position adjacent the end wall 30 by lugs 30a and 32a in the manner above described. For convenience in handling the coil forms and their supporting structures and for mounting them in the casing, as well as for providing flexibility in the number of coil forms that may be employed in any particular case, it is preferred that each pair of coil forms 56 and 57 which are disposed one above the other, be provided with its individual supporting member 60. The coil forms 56 and 57 support ferro-magnetic cores 61 and 62 movable axially in said coil forms and connected by slender rods 55 and 63 with the transverse member 54 of the cross-head, as a result of which all of the cores of the mechanism illustrated in Fig. 12 are simultaneously moved in the same direction and to the same amount, depending on the amount of angular movement imparted to the shaft 35.

In some cases, it is desired to use more than two tuning units in a single horizontal plane, instead of providing the structure with two of said units as shown in Fig. 1. This is readily accomplished as illustrated in Fig. 13 by expanding the structure of Fig. 1 laterally by an amount determined by the number of tuning units it is desired to mount in the same housing. In this case, the end walls 64 and 65 and the bottom wall 66 are of the same construction described in connection with Fig. 1, the only difference being that they are of greater extent laterally between the side walls 67 and 68, which side walls have the same construction as shown in Figs. 1 and 2. With the construction of Fig. 13, the transverse member 69 of the cross-head has the same construction and form of mounting as the transverse member 13 shown in Fig. 1, the only difference being that it is sufficiently longer than the transverse member 13 to extend between the side walls 67 and 68 in the positions they have determined by the number of tuning units employed in the casing of the tuning mechanism. All of the axially movable ferro-magnetic cores 70 employed with the structure illustrated in Fig. 13 are connected by slender rods 71 with the transverse member 69 for simultaneous movement in the same direction and to the same extent by angular movement of the shaft 72, depending upon the extent of said movement, in the same manner described above in connection with the apparatus shown in Figs. 1, 2 and 4. The cores 70 shown in Fig. 13 cooperate with coil forms in the same manner described in connection with Figs. 1, 2 and 4, and

said coil forms are supported in the casing of the mechanism in the same manner as above described in connection with Figs. 1, 2 and 4 and may conveniently be provided with tuning capacitors 19, one for each of the tuning units and supported in the same manner above described in connection with Figs. 1, 2 and 4 for the capacitors 28 and 29. It will at once appear that the structure illustrated in Figs. 5, 6 and 7 may be expanded in the same manner as illustrated in Fig. 13 for the structure shown in Fig. 1, where it is desired to employ more than two tuning units in a single horizontal plane, and at the same time use the arrangement of parts illustrated in Figs. 5, 6 and 7.

While I have shown my invention in the particular embodiments above described, it will be understood that I do not limit myself thereto as I may employ equivalents thereof without departing from the scope of the appended claims.

Having thus described my invention, what I claim is:

1. A permeability tuning mechanism for radio purposes for moving cores axially in associated coil forms, including in combination a frame for supporting a coil form and having parallel and laterally spaced side walls, a rotatable shaft extending at right angles between said side walls, a pair of drums of the same effective diameter secured to said shaft in spaced relation, a cross-head slidably mounted for movement longitudinally of said side walls and extending transversely therebetween, a flexible band around each of said drums and connected with portions of said cross-head spaced apart in the direction of its movement, and a core-operating rod extending from said crosshead and in the direction of movement of said crosshead.

2. A permeability tuning mechanism for radio purposes for moving cores axially in associated coil forms, including in combination a frame for supporting a coil form and having parallel and laterally spaced side walls, a rotatable shaft extending at right angles between said side walls, a pair of drums of the same effective diameter secured to said shaft in spaced relation, a cross-head slidably mounted for movement longitudinally of said side walls and extending transversely therebetween, a flexible band around each of said drums and connected with portions of said crosshead spaced apart in the direction of its movement, a core-operating rod extending from said crosshead and in the direction of movement of said crosshead, and guide means in line with each of said drums and guiding the corresponding flexible band.

3. A permeability tuning mechanism for radio purposes for moving cores axially in associated coil forms, including in combination a frame for supporting a coil form and having parallel and laterally spaced side walls, a rotatable shaft extending at right angles between said side walls, a pair of drums of the same effective diameter secured to said shaft in spaced relation, a cross-head slidably mounted for movement longitudinally of said side walls and extending transversely therebetween, a flexible band around each of said drums and connected with portions of said cross-head spaced apart in the direction of its movement, a core-operating rod extending from said crosshead and in the direction of movement of said crosshead, and guide means in line with each of said drums and guiding the corresponding flexible band, said guide means comprising idler rollers supported by said side walls.

4. A permeability tuning mechanism for radio purposes for moving cores axially in associated coil forms, including in combination a frame for supporting a coil form and having parallel and laterally spaced side walls, a rotatable shaft extending at right angles between said side walls, a pair of drums of the same effective diameter secured to said shaft in spaced relation, a cross-head slidably mounted for movement longitudinally of said side walls and extending transversely therebetween, a flexible band around each of said drums and connected with portions of said cross-head spaced apart in the direction of its movement, and a core-operating rod extending from said crosshead and in the direction of movement of said crosshead, said crosshead comprising side members of formed sheet metal slidably mounted on said side walls and a transverse member of insulating material connected at its ends with said side members.

5. A permeability tuning mechanism for radio purposes for moving cores axially in associated coil forms, including in combination a frame for supporting a coil form and having parallel and laterally spaced side walls, a rotatable shaft extending at right angles between said side walls, a pair of drums of the same effective diameter secured to said shaft in spaced relation, a cross-head slidably mounted for movement longitudinally of said side walls and extending transversely therebetween, a flexible band around each of said drums and connected with portions of said cross-head spaced apart in the direction of its movement, and a core-operating rod extending from said crosshead and in the direction of movement of said crosshead, said crosshead comprising side members of formed sheet metal slidably mounted on said side walls and a transverse member of insulating material connected at its ends with said side members, said side walls having longitudinal slots therethrough, and said side members having retaining lugs extending therefrom and into said slots.

6. A permeability tuning mechanism for radio purposes for moving cores axially in associated coil forms, including in combination a frame for supporting a coil form and having parallel and laterally spaced side walls, a rotatable shaft extending at right angles between said side walls, a pair of drums of the same effective diameter secured to said shaft in spaced relation, a cross-head slidably mounted for movement longitudinally of said side walls and extending transversely therebetween, a flexible band around each of said drums and connected with portions of said cross-head spaced apart in the direction of its movement, a core-operating rod extending from said crosshead and in the direction of movement of said crosshead, and guide means in line with each of said drums and guiding the corresponding flexible band, said crosshead comprising side members of formed sheet metal slidably mounted on said side walls and a transverse member of insulating material connected at its ends with said side members.

7. A permeability tuning mechanism for radio purposes for moving cores axially in associated coil forms, including in combination a frame for supporting a coil form and having parallel and laterally spaced side walls, a rotatable shaft extending at right angles between said side walls, a pair of drums of the same effective diameter secured to said shaft in spaced relation, a cross-head slidably mounted for movement longitudinally of said side walls and extending transversely

therebetween, a flexible band around each of said drums and connected with portions of said cross-head spaced apart in the direction of its movement, a core-operating rod extending from said crosshead and in the direction of movement of said crosshead, and guide means in line with each of said drums and guiding the corresponding flexible band, said crosshead comprising side members of formed sheet metal slidably mounted on said side walls and a transverse member of insulating material connected at its ends with said side members, said side walls having longitudinal slots therethrough, and said side members having retaining lugs extending therefrom and into said slots.

8. A permeability tuning mechanism for radio purposes for moving cores axially in associated coil forms, including in combination a frame for supporting a coil form and having parallel and laterally spaced side walls, a rotatable shaft extending at right angles between said side walls, a pair of drums of the same effective diameter secured to said shaft in spaced relation, a cross-head slidably mounted for movement longitudinally of said side walls and extending transversely therebetween, a flexible band around each of said drums and connected with portions of said cross-head spaced apart in the direction of its movement, a core-operating rod extending from said crosshead and in the direction of movement of said crosshead, and guide means in line with each of said drums and guiding the corresponding flexible band, said guide means comprising idler rollers supported by said side walls, said cross-head comprising side members of formed sheet metal slidably mounted on said side walls and a transverse member of insulating material connected at its ends with said side members.

9. A permeability tuning mechanism for radio purposes for moving cores axially in associated coil forms, including in combination a frame for supporting a coil form and having parallel and laterally spaced side walls, a rotatable shaft extending at right angles between said side walls, a pair of drums of the same effective diameter secured to said shaft in spaced relation, a cross-head slidably mounted for movement longitudinally of said side walls and extending transversely therebetween, a flexible band around each of said drums and connected with portions of said cross-head spaced apart in the direction of its movement, a core-operating rod extending from said crosshead and in the direction of movement of said crosshead, and guide means in line with each of said drums and guiding the corresponding flexible band, said guide means comprising idler rollers supported by said side walls, said cross-head comprising side members of formed sheet metal slidably mounted on said side walls and a transverse member of insulating material connected at its ends with said side members, said side walls having longitudinal slots therethrough, and said side members having retaining lugs extending therefrom and into said slots.

WILLIAM A. SCHAPER.
